UNITED STATES PATENT OFFICE.

DOUGLAS COLLINS, OF SALISBURY, NORTH CAROLINA.

STONEWORKING MACHINE.

Application filed February 14, 1924. Serial No. 692,770.

To all whom it may concern:

Be it known that I, DOUGLAS COLLINS, a citizen of the United States, residing at Salisbury, in the county of Rowan and State 5 of North Carolina, have invented certain new and useful Improvements in Stoneworking Machines, of which the following is a specification.

My present invention relates to improvements in stone working machines of the 10 multiple spindle or gang type wherein a plurality of chisels and machine tools therefore are employed for the purpose of tracing or grooving the surface of a stone or 15 other object.

As herein exemplified the invention is designed for the purpose of tracing or grooving a chunk of stone preliminary to breaking the traced or grooved stone into sections 20 or slabs which breaking is accomplished by the use of hammer blows applied in suitable manner.

In the production of paving blocks for use on streets the hard stone, as granite, is 25 taken from the quarry in cubical chunks and the faces of the cube or chunk are marked with parallel lines as guides for cutting the cube into slabs; these slabs are then cut into blocks; and the blocks are 30 finally cut into paving stones.

The primary object of my invention is to provide a machine which will supplant the customary manual labor employed in 35 chiselling or tracing a groove on the marked line of the chunk or cube as above indicated, and to accomplish this purpose I utilize a number of machine tools which are supplied with motive fluid as steam or compressed air. The machine tools are 40 equipped with reciprocating chisels for cutting the grooves, and means are provided for supporting, adjusting, and operating these tools in such manner as to expedite the required grooving or tracing of the surfaces 45 of the cube or chunk of stone. By carrying out my invention as a step in the manufacture of paving blocks or stones substantial advantages are secured in that time and labor are saved, the cubes are accurately 50 grooved to insure breaking into uniform and properly shaped slabs, and consequently the cost of production of the paving stones is reduced and their value enhanced.

The invention consists in certain novel 55 combinations and arrangements whereby the horizontally operating machine tools are

caused to cut the stone while moving in vertical planes as hereinafter described and as illustrated in my accompanying drawings wherein the parts are combined and arranged in accord with the best mode I have thus far devised for the practical application of the principles of my invention. Changes and alterations in the exemplified construction are contemplated and may be 60 made within the scope of my claims without departing from the spirit of my invention. 65

Figure 1 is a view in side elevation of a machine embodying my invention.

Figure 2 is a horizontal sectional view, 70 at line 2-2 of Figure 1.

Figure 3 is a front elevation of the machine with parts in section for convenience of illustration.

In order that a clear understanding of 75 the invention may be obtained I have illustrated as S a cube or chunk of stone as granite as it comes from the quarry, with parallel lines T marked thereon along which lines the grooves are to be traced. The 80 stone or chunk is conveyed or transported from the quarry and through the stone working plant on cars indicated at C in Figure 1 which run on industrial railways, and the body of the car is rotatable in order 85 that various faces of the chunk or cube can be presented to the stone working machines, the latter preferably being stationed at permanent locations.

In the drawings the machine is adapted 90 to cut three parallel grooves, but it will be understood that changes may be made to adapt the machine for tracing a larger or smaller number of these grooves if desired.

For cutting the grooves three chisels are 95 indicated as 1 which are fashioned with beveled cutting edges 2 to readily adapt them for use in forming the groove as the chisels pass across the face of the cube or chunk. Three machine tools 3, 4, and 5 of standard type utilizing motive fluid, as compressed air, are employed which are disposed in a horizontal plane and adapted when in operation to reciprocate the chisels for cutting the grooves. These machine tools are supported and relatively movable in bushings 6, 7, and 8, and at 9 provision is made for attachment of flexible pipes or hose to the machine tools for the required supply of motive fluid. The machine tools 100 are each fashioned with a head as 10 which co-acts with the bushings 6, 7, and 8 to pre- 105

vent excessive movement of the machine tool, and the usual handle 11 is employed and adapted for use in my machine as will hereinafter be described.

5 To prevent displacement of the loosely carried chisels a spring 12 is attached to a collar 13 on the chisel shank and the end of the spring is anchored to the machine tool in suitable manner.

10 The cube as illustrated in Figure 1 of the drawings is approximately twenty six inches, and the lines T to be traced are approximately six and one half inches apart, but the distance between these lines may be varied

15 in proportion to the size of the cube, and therefore the machine tools are capable of adjustment toward or away from each other. That is the two machine tools 3 and 5 may be laterally adjusted with relation to the

20 central, fixed tool 4. For this purpose the outer bushings 7 and 8 are provided with laterally extending flanges 14 fashioned with alined slots 15 and set bolts 16 are utilized to hold the flanged bushings in ad-

25 justed position. A head plate 17 which supports the two outer bushings is fashioned integral with the central bushing, or the bushing and cross head may otherwise be made rigid. The set bolts 16 are rigid with

30 the head plate and pass upwardly through the slotted flanges, and usual clamping nuts are employed to clamp the adjustable bushings and their machine tools in position. Other means may be employed for adjusting

35 and securing these adjustable machine tools on the head plate for varying the distance between the central fixed bushing and the two outer bushings. Graduated scales are

40 indicated in Figure 3 at the front of the bushings and head plate as guides in the adjustment of the bushings.

The machine tools are carried by the cross head 17' and these members are supported to move bodily in a vertical plane in order

45 that the chisels may be reciprocated and caused to traverse the surface of the stone during the cutting operations.

The cross head and its machine tools may be elevated by the same motive fluid as em-
50 ployed for the operation of the machine tools, and these elements may be permitted to descend when the pressure of the motive fluid is withdrawn. For this purpose I utilize an upright cylinder 18 fixed beneath

55 the cross head and provided with a piston 19 and rod 20 of the rectilinear type, to the upper end of which rod the cross head is rigidly secured as seen in Figure 3. Motive fluid may be admitted to the cylinder below

60 the piston through the pipe 21 and controlled by the valve 22, and the cylinder may be provided with a vent as 23 near its upper end.

At its extremities the cross head carries a

65 pair of elements which are both fashioned

with a horizontally disposed guide block 24 and a vertically disposed slide block 25, the latter being movable in a vertical plane in a rectangular frame comprising a bottom horizontal bar 26 and upright side bars 27. 70 These side bars are grooved at their inner sides to form guide ways 28 for retaining and guiding the slide blocks 25 of the cross head as the latter is elevated by fluid pres-
75 sure in the cylinder and permitted to de-
scend when pressure is released below the elevated position. From this description it will be apparent that the cross head and ma-
chine tools may be reciprocated vertically
80 to cause the chisels to cut or trace vertical grooves in the adjacent face of the cube.

The bottom bar 26 of the rectangular frame or main frame of the machine is rig-
85 idly supported from the cylinder and in this instance is fashioned to form the upper head of the cylinder through which the piston rod passes and in which it has the re-
quired slide bearing.

The machine tools are adjustable along their longitudinal axes with relation to the 90 cross head and the bushings carried thereby, and a horizontally disposed frame 29 having heads 30 and grooves 31 for the guide blocks 24 is employed. The frame is supported to slide horizontally on these blocks and the 95 rear cross bar 32 of this adjusting frame is used for the application of power from a handlever 33 pivoted at 34 in the frame and suspended to swing therefrom. The lever is supported from a bracket 35 attached to the cross head 17 and the pivotal point of the lever is at 36 in this bracket in order that as the free end of the lever is swung to the left in Fig. 1 the adjusting frame may be 100 slid to the right. A pawl 37 on the lever is used to co-act with a rack 38 on the bracket 105 for holding the adjusting frame in operative position.

The operation of the three machine tools is simultaneously controlled to start and 110 stop, by manual power, and a single operat-
ing or control cross bar 40 and angularly dis-
posed parallel rods 41 carried by the cross bar are utilized. These parallel rods 41 have 115 sockets 42 which encase and connect with the handles 11 of the respective machine tools and co-act with the handles for controlling the operation of the mechanism within the machine tools. The rods move in actual alignment with the machine tools and are actuated from the cross bar by means of a control lever 43 pivoted at 44 in a bracket 45 projecting forwardly and upwardly from the cross head 17 to which the bracket is at-
tached. The rods are guided in a plate 46 having slots therethrough as indicated at 47, and springs 48 interposed between this plate and the cross bar 40 tend to hold the machine tools idle. The slotted guide plate 46 is sup-
120 ported in the adjusting frame by means of 130

bolts 49 and pins 50 of the slotted plate which pass through complementary slots 51 of the adjusting frame or the side bars 29 thereof.

- 5 When the outer bushings 7 and 8 are adjusted laterally with relation to the fixed bushing 6 the rods 41 move bodily with these bushings and therefore the control bar 40 is slotted at 52 for the rods.
- 10 For supporting the cutting ends of the chisels I utilize a bracket 53 supported from the head plate 17' and provided with laterally adjustable sections 54 and collars 55, it being understood that the supporting brackets are adjustable to compensate for adjustment of the bushings 7 and 8.

The adjusting frame composed of the head plate 17' side bars 29 and rear cross bar 32 and disposed in horizontal position 20 is carried bodily in the vertical movement of the cross head, and this frame is bodily movable, transversely of the cross head, and guided by the blocks 24 of the cross head and grooves 31 of the heads 30 of the 25 horizontal frame. The two outer bushings and their machine tools are adjustable laterally of the central bushing and its tool.

In preparing for the tracing or grooving operation of the machine, the lever 33 is first pulled outwardly to slide the adjusting frame including the head plate 17, the bushings and the machine tools toward the stone until the beveled cutting edges of the chisels engage the stone. A continued pull 35 on the lever causes a further movement of the head plate and bushings with the adjusting frame, and as the machine tools are in engagement with and obstructed by the stone these latter elements remain stationary as the bushings slide over them. A gap is thus formed between the heads 10 of the machine tools and the adjoining ends of the bushings, said gap being the width of the depth of the groove to be cut by the 40 chisels. By use of the pawl 37 and ratchet 38 the adjusting frame is locked in position. If the machine tools are in the position of Figures 1 and 2 motive fluid pressure is now admitted to the elevating mechanism and at the same time the control lever 43 is pulled to the left in Figure 1 for starting the operation of the tools. The three operating machine tools are thus elevated causing the reciprocating chisels 45 to traverse the surface of the stone and cut their respective grooves. When the elevated position is reached, the motive fluid pressure may be released from the cylinder and the continually operating chisels will 50 cut the groove on the down movement of the cross head and machine-tool frame.

The necessary number of reciprocations are made until the required depth of the groove is cut.

Should irregularities in the surface be 65 encountered by a chisel, as for instance a projection of stone, the cylinder of the chisel will be backed through its bushing against the tension of a spring 48 to compensate for this obstruction and after the 70 obstruction is passed the cylinder and chisel are returned to projected position.

After one face of the chunk has been grooved the cube may be turned to present 75 successively other faces for grooving as described in preparing the cube for subsequent breaking into slabs.

Having thus fully described my invention, what I claim as new and desire to secure by Letters Patent is—

1. The combination with a vertically movable cross head and a transversely adjustable frame including a head plate, of a fixed central bushing on the head plate and a machine tool supported therein, laterally disposed bushings carried by said head plate and means for adjusting said bushings relatively to the fixed bushing, and machine tools supported in said laterally disposed bushings.

2. The combination with a vertically movable cross head and a transversely adjustable supporting frame, of a fixed central bushing carried by said frame and a machine tool supported therein, lateral 95 bushings carried by said frame and machine tools supported therein, and means for adjusting the lateral bushings relatively to the fixed bushing.

3. The combination with a vertically movable cross head having end guide blocks, of a transversely adjustable supporting frame having complementary grooves for said blocks and means for moving said frame, supporting bushings carried by said frame, machine tools carried in said bushings, and means for laterally spacing some of said bushings with relation to the frame.

4. The combination with a motive fluid cylinder and main frame supported thereon of a piston and rod and a cross head guided in said frame, of an adjusting frame supported on the cross head and movable transversely thereof, laterally adjustable bushings carried by said adjusting frame, machine tools supported in said bushings and means for moving said adjusting frame relative to the work.

In testimony whereof I affix my signature.

DOUGLAS COLLINS.
